(57) **CLAIM**

The ornamental design for a shade structure, as shown and described.

DESCRIPTION

FIG. 1 is a perspective view of the shade structure of the subject disclosure;

FIG. 2 is a front side elevation view of the shade structure of FIG. 1;

FIG. 3 is a rear side elevation view of the shade structure of FIG. 1;

FIG. 4 is a right elevation view of the shade structure of FIG. 1;

FIG. 5 is a left elevation view of the shade structure of FIG. 1;

FIG. 6 is a top elevation view of the shade structure of FIG. 1; and,

FIG. 7 is a bottom elevation view of the shade structure of FIG. 1.

The shading in the drawings is for illustrative purposes only and does not form part of the claimed design.
